DESIGN FOR AN EGG TRAY OR THE LIKE

Hollie C. Gulley, Los Angeles, Calif.

Application February 15, 1947, Serial No. 136,929

Term of patent 3½ years

(Cl. D44—10)

To all whom it may concern:

Be it known that I, Hollie C. Gulley, a citizen of the United States, residing in Los Angeles, in the county of Los Angeles and State of California, have invented a new, original, and ornamental Design for an Egg Tray or the like, of which the following is a specification, reference being had to the accompanying drawing, forming part thereof.

The figure is a perspective view of an egg tray or the like, showing my new design in a slightly extended position.

I claim:

The ornamental design for an egg tray or the like, substantially as shown.

HOLLIE C. GULLEY.
